CLAIM

The ornamental design for a covered swivel rotary file, as shown and described.

DESCRIPTION

FIG. 1 is a front perspective view of a covered swivel rotary file showing our new design;

FIG. 2 is a front elevational view on an enlarged scale;

FIG. 3 is a top plan view;

FIG. 4 is a right side elevational view, the opposite side being mirror image thereof;

FIG. 5 is a rear elevational view; and

FIG. 6 is a bottom plan view thereof.
